IMPROVEMENT IN SLIDE VALVES.

W. B. ROBINSON, OF DETROIT, MICHIGAN.

Letters Patent No. 60,252, dated December 4, 1866.

SPECIFICATION.

TO ALL WHOM IT MAY CONCERN:

Be it known that I, W. B. ROBINSON, of Detroit, in the county of Wayne, and State of Michigan, have invented a new and improved Steam Valve; and I do hereby declare that the following is a full, clear, and exact description thereof, which will enable others skilled in the art to make and use the same, reference being had to the accompanying drawings, forming a part of this specification, in which—

Figure 1 represents a longitudinal vertical section of this invention.

Figure 2 is a horizontal section of the same.

Similar letters of reference indicate like parts.

This invention consists in a counterbalance in combination with exhaust-passages in the valves in such a manner that the exhaust steam is passed in a direct course through the valve, counterbalance, and steam-chest cover; and furthermore, the cost of the valve and the engine is reduced, and steam is economized by shortening the ports in the cylinder to the thickness of said cylinder or of the valve-seat.

A represents a valve-chest, which communicates with the cylinder, B, through ports, α α' , situated close to the ends of said cylinder, and passing straight through that side of the same which forms the seat for the valves, C C'. These two valves are connected by the arched bridge, D, and they are at such distance apart, that when the valve, C', covers the port, α' , the port, α , is open, and vice versa. From the bridge, D, rises the counterbalance, E, which is composed of a cylindrical projection, provided at its top edge with suitable packing rings, which work steam tight against the inner surface of the steam-chest cover. The superficial area of the counterbalance is so regulated that the valve is as near as possible balanced, and that the same works with the least possible friction. The exhaust steam passes off through channel, δ , in the interior of the bridge, D, and through the interior of the cylindrical projection, E, in a more direct course than in ordinary steam engines, thus rendering the exhaust free and relieving the piston of all back pressure.

By this arrangement the construction of the steam cylinder is considerably simplified, the friction surface of the steam valve is reduced, and steam is economized by shortening the steam ports in steam cylinder to the thickness of cylinder and valve face.

What I claim as new, and desire to secure by Letters Patent, is—

The combination of the counterbalance E, having suitable packing rings, and the bridge D, with its passage δ and valve C C', arranged with the valve chest A, and cylinder B, provided with port α α' , and operating substantially as described for the purpose specified.

WILLIAM B. ROBINSON.
